Primary Examiner — Janice Hallmark*Assistant Examiner* — Omeed Agilee(74) *Attorney, Agent, or Firm* — Dinsmore & Shohl, LLP(57) **CLAIM**

The ornamental design for a cot fastener, as shown and described.

DESCRIPTION

FIG. 1 is a perspective view of a cot fastener;

FIG. 2 is a front elevation view thereof;

FIG. 3 is a left side elevation view thereof.

FIG. 4 is a rear elevation view thereof;

FIG. 5 is a right side elevation view thereof

FIG. 6 is a top plan view thereof; and,

FIG. 7 is a bottom plan view thereof.

The broken lines depict portions of the cot fastener that form no part of the claimed design.
